UNITED STATES PATENT OFFICE.

ROSWELL F. COOK, OF ILION, NEW YORK, ASSIGNOR TO E. REMINGTON & SONS, OF SAME PLACE.

MAGAZINE FOR FIRE-ARMS.

SPECIFICATION forming part of Letters Patent No. 313,851, dated March 17, 1885.

Application filed November 15, 1884. (Mod. del.)

To all whom it may concern:

Be it known that I, ROSWELL F. COOK, of Ilion, in the county of Herkimer and State of New York, have invented certain new and useful Improvements in Magazines for Fire-
5 Arms, of which the following is a specification.

This invention relates to that class of cartridge magazines or boxes designed to be used with the gun patented to J. Lee, November 10 4, 1879, No. 221,328; and the invention consists in a novel construction of the spring which supports and raises the cartridges in the box, all as hereinafter more fully set forth.

Figures 1 and 3 are side elevations of a magazine or box with its front side removed to illustrate the construction and operation of the spring, and Fig. 2 is a perspective view of the spring detached from the box.

Various styles of springs have heretofore 20 been devised for use in these boxes, some of zigzag form, others coiled, and still others curved, with a rigid arm attached; but in all cases they have been made of flat strips or pieces of steel. Many objections have been 25 found to exist to these flat springs, it being somewhat difficult to secure a perfectly-uniform temper, and they being too expensive. Moreover, they do not possess the degree of elasticity that is desired for this purpose, and 30 are liable to become set or to break when kept compressed for a long time, as they must be when the boxes are filled with cartridges, thus destroying the efficiency of the magazine.

The object of my present invention is to provide 35 these magazine-boxes with a spring which will obviate all these difficulties or objections, which can be compressed into a small space, and shall be cheap to manufacture. To accomplish this, I make the spring B of wire, 40 as represented in the drawings, preferably using steel wire for the purpose, though that is not absolutely necessary. To construct this spring, I take a piece of wire of the proper length and bend it into a series of coils or 45 folds, as shown in the drawings, these coils or folds being made to conform to the shape of the box A, they being slightly shorter and narrower than the interior space of the box, so as not to bind therein when compressed, 50 but at all times to have free play therein. The

spring shown is composed of four folds or coils, the ends of each of the outer folds or coils being bent backward and extended back far enough to afford a flat bearing at both terminals or ends, so as to prevent any tendency of the spring to tip sidewise when compressed, 55 as shown at n, Fig. 2. As shown in Fig. 2, these bearing ends are both at the front, so that when placed in the box and the follower l with the cartridges C are placed thereon the 60 spring will naturally exert its pressure primarily on the front part of the follower, thus keeping the front end or point of the cartridges elevated, as is necessary to enable them to be shoved from the top of the box directly into 65 the chamber of the gun.

By examining Fig. 1, it will be seen that the coils of the spring are so arranged that the front end, a, of each projects slightly in advance of the one next below it, so that when 70 compressed the several folds will overlap each other, thus causing them to move parallel with the front of the box. This is effected by giving a different inclination to the alternate bars of the various folds or coils, as shown in Fig. 75 1, in which it will be seen that the bar o of each fold is more inclined than the bar m of the same fold or coil, as shown more clearly in Fig. 1. If the coils or folds be made of uniform length, their rear ends will also overlap 80 in the same manner, and I so prefer to make them, as I find the spring thus made to operate perfectly. Still it is obvious that if desired the coils or folds, especially the intermediate ones, may be made of a different length from 85 the others; but if made shorter it will decrease to that extent the elasticity of the spring, which is not desirable.

While I have shown the spring as having 90 four folds or coils, I do not confine it to that number, as it is obvious that more or less may be used. A less number will decrease somewhat the elasticity of the spring, while a greater number will occupy more space in the box, which it is desirable to avoid as far 95 as possible, and yet secure a sufficient extent of spring to possess the required degree of force and elasticity and bear the requisite compression without danger of breaking or being set.

It will be seen that each of the bars *o* and *m* which compose the spring act as springs, and that thus the spring is extended over a much greater extent or length of spring than is the case with any of the various forms of flat springs heretofore used in these boxes, and that, consequently, there is much less danger of breaking or injuring the spring when compressing it, and there is a correspondingly greater degree of elasticity to the spring. By slightly bending the two outer bars, as shown in Fig. 2, opposite the points where the bent ends *n* terminate, the spring will bear only for a short distance on the outer bars, thereby leaving the balance of those bars also to exert their spring force.

The advantages of this spring for the purpose are obvious, and its simplicity and cheapness of construction, as well as its greater efficiency and durability, render it especially valuable in this connection, more particularly as when these boxes are used for military purposes they are expected to be thrown away, and in which case, as on a march, the springs are liable to be kept compressed for long periods of time, as the boxes will of course be carried filled, ready for instant use.

I am aware that wire springs have been made with both round and oval coils, and I do not claim such; but,

Having described my invention, what I claim is—

1. In combination with a cartridge-box, substantially such as shown, the wire spring *B*, composed of a series of coils or folds made to conform to the shape of the box transversely, substantially as shown and described. 35

2. A spring for magazine-boxes, composed of a piece of spring-wire coiled or folded to correspond to the interior of the box, and having its terminal or bearing ends arranged at the front, whereby its pressure is brought to bear upon the front portion of the follower, and thus keep the front end of the cartridges elevated, substantially as shown and described. 45

3. In combination with a cartridge-box, substantially such as shown, the spring *B*, composed of spring-wire bent or folded into a series of coils or folds, with the front end of each coil or fold overlapping or projecting beyond the one next below it, whereby the ends of said coils or folds are caused to move in a line parallel with the front or inclined end of the box, substantially as shown and described. 50
